UNITED STATES PATENT OFFICE.

ANTHONY ZIMNIEWICZ, OF NEW YORK, N. Y.; ASSIGNOR, BY MESNE ASSIGNMENTS, TO MIEHLE PRINTING PRESS & MANUFACTURING COMPANY, OF CHICAGO, ILLINOIS, A CORPORATION OF ILLINOIS.

HIGH-SPEED COLLECTING CYLINDER.

Application filed December 15, 1924. Serial No. 758,111.

My present invention relates to improvements in high speed collecting cylinders adapted especially for use on printing presses in the operation of folding printed 5 sheets or webs. The primary object of the invention is to improve the construction of the collecting cylinder as a whole in order that it may revolve at comparatively high speed and rapidly perform its required 10 functions with efficiency. By the utilization of my invention in the construction and operation of the collecting cylinder, a facile co-operation of the grippers and tucking blade are insured for folding the sheet or 15 web and means are provided for relatively adjusting the position of the grippers and tucking blade to adapt the device for various purposes. The construction, adjustment and operation of the collecting cylinder are 20 otherwise simplified and improved as will be hereinafter more fully pointed out and claimed.

The invention consists in certain novel combinations and arrangements of parts involving the collecting cylinder, the single 25 tucking blade and complementary set of grippers, and accessories to be set forth. In the accompanying drawings I have illustrated one complete example and a slight 30 modification of my invention, wherein the parts are combined and arranged according to the best mode I have thus far devised for the practical application of the principles of my invention.

Figure 1 is a view in side elevation of a collecting cylinder constructed according to and embodying my invention, the cylinder being shortened at the right of the center line for convenience of illustration.

Figure 2 is an end elevation of the cylinder as a whole as seen from the left in Figure 1.

Figure 3 is an enlarged detail sectional view, transversely of the tucking blade showing the manner of securing it in place in the cylinder.

Figure 4 is a detail view of one of the pair of cam actuated gripper operating devices.

Figure 5 is a transverse sectional view 50 through the body of the cylinder and its accessories with the grippers free or open in full line position and closed in dotted position.

Figure 6 is a detail view showing the grippers in closed position.

Figure 7 is a fragmentary view showing a modification of my invention wherein the collecting cylinder and the jaw cylinder are provided with complementary meshing gears.

In carrying out my invention I utilize a single set of grippers including main and auxiliary grippers, and a complementary tucking blade. The grippers and tucking blade are carried by different elements of the collecting cylinder whereby the position of the set of grippers may be changed with relation to the tucking blade in adapting the collecting cylinder to various sizes or lengths of paper sheets or webs to be folded.

In the preferred form of the invention I use a hollow printing press cylinder 1, which as shown in Figure 1 is foreshortened for convenience of illustration at the right of its center line. The cylinder is fashioned with end heads 2 and 3 and at suitable intervals on its periphery is provided with annular ribs as 4 for contact with the sheet or web of paper that is to be grasped by the grippers as the collecting cylinder rotates or revolves at high speed. The cylinder is carried on a horizontal shaft 5 extending longitudinally through the cylinder, interior hubs or bosses 6 being provided on the cylinder to insure stability, and the shaft is journaled to revolve in suitable bearings in the frame of the printing machine in customary manner.

The tucking blade 7 which extends longitudinally of the cylinder and transversely of the direction of travel of the paper sheet or web to be folded, is carried and projects from the exterior periphery of the cylinder, which latter is flattened at 8 and its wall thickened for the accommodation of the blade. Said blade projects the proper distance from the body of the cylinder for the performance of its function in connection with the jaw cylinder and the blade is fitted into an external groove or mortise 9 that extends the full length of the cylinder and forms a depression in the flat face 8. The blade is affixed to a tenon or bar 10 as by screws 11, and the bar and blade are seated in the mortise or groove by means of radially extending screws 12.

At the exterior of the cylinder ends are provided a pair of circular adjusting plates or disks 13 and 14 of complementary construction and provided with exterior hubs 15 loose on the shaft 5. By means of three spaced clamp bolts 16 for each plate the latter are secured at the ends of the cylinder to form a rigid construction, of which the cylinder and plates comprise the collecting cylinder. The clamping bolts 16 which bind the plates to the cylinder have washers 16' and pass through arcuate slots 17 in the plates. The three bolts are spaced at suitable intervals about the center of the plate and are threaded into complementary bolt holes in the ends 2 and 3 of the cylinder. The bolts in addition to clamping or binding together the blades and cylinder, co-act with the slots of the plates to guide the latter when they are being turned or adjusted on the shaft with relation to the cylinder. When the bolts are loosened and the plates otherwise freed from the cylinder the plates may be turned on the shaft 5 with a simultaneous movement to adjust the grippers which are carried by the plates with relation to the tucking blade that is carried by the cylinder intermediate of the plates.

For this adjustment I utilize a pair of rack wheels or pinions 18 fixed on the ends of a shaft 19 which extends longitudinally through the cylinder and is journaled in the end walls thereof. The ends of this adjusting shaft project through the cylinder walls and also through a pair of arcuate slots 20 in the adjacent plates 13 and 14. One end of the shaft as 21 is squared in order that it may accommodate a tool or wrench and by means of the tool the shaft may be turned manually to turn the rack wheels.

Each adjusting plate on its outer face has affixed thereto a segmental rack or toothed plate 22 of suitable length for co-action with the respective rack wheels, and it will be apparent that, when the plates are loosened with respect to the cylinder, the two end plates may be turned on their centers with relation to the cylinder by the co-action of the rack wheels and segmental racks 22.

A pair of diametrically arranged brace bars 23 which extend longitudinally through the cylinder are passed through arcuate slots 24 in the end walls of heads of the cylinder. The ends of these brace bars are anchored in the respective end plates 13 and 14 by means of bolts 25 which pass through the slots 24 and are threaded into the threaded socket ends of the brace bars. These brace bars which add rigidity and stability to the collecting cylinder as a whole, are of course loosened when the adjusting plates are to be adjusted.

The collecting cylinder is equipped with two series of grippers forming a co-acting set of which 26 indicate the auxiliary series

and 27 the main series of grippers. The elements 26 and 27 are flat metallic plates of the required resiliency and fashioned to proper shape or form for the performance of their functions. They are carried by the end plates of the collecting cylinder for co-action with the pad-bar 28 and the web or paper is gripped by these members as indicated in full lines Figure 6 and dotted lines Figure 5. The pad-bar is also carried by the adjusting plates and is interposed between them and secured rigidly thereto by means of stud bolts 29 on the ends of the pad-bar that extend through bolt holes in the plates, and clamp nuts 30 on the outer sides of the plates secure the pad bar in position. Pins or screws 29' may also be passed through the adjusting plates from the outside to engage the ends of the pad-bars to insure rigidity after they are accurately adjusted to position.

The paper sheet or web of course is grasped or gripped between the set of grippers or fingers and the outer face of the pad-bar which is approximately flush with the periphery of the cylinder, and as the cylinder rotates the paper is carried around by the cylinder for further manipulation by the tucking blade after the paper has been released from the grippers.

The two series of grippers forming the set are carried on a pair of parallel rock shafts 31 and 32 which extend longitudinally through the cylinder, the end walls and body of the cylinder being cut away or cut out as at 33 to accommodate the gripper mechanism. The grippers or clamping fingers are bolted or otherwise secured on split blocks 34 that encase the shafts and one of the securing bolts, as 35 for each gripper is used for clamping the split block on its shaft. It will readily be seen that the grippers, through the blocks, may be adjusted both longitudinally and circumferentially on their rock shafts to the required operative position. The grippers are spaced apart at regular intervals along the rock shafts as indicated in Figure 1 to suit various conditions.

The two rock shafts are located in the opening 33 of the cylinder and are journaled at their ends in the two adjusting plates 13 and 14. These rock shafts are actuated at regular intervals to cause the grippers to grasp the paper sheet or web in combination with the pad-bar, and an actuating cam, (not shown) or other suitable device is provided at each end of the collecting cylinder to co-act with tripping mechanism for this purpose. The shafts at opposite ends project through the adjusting plates and a trip lever, as 36 and 37 is fixed to each projecting end of the shafts by means of a hub or boss 38 located at the outer sides of the plates. Each lever carries a roller as 39 for engagement with an actuating cam and the move-

ment of the levers is guided and controlled by means of a rod as 40, 40'. These rods are pivoted at 41 on one arm of a lever and the rods are suitably fitted to slide in an opening 5 42 of a fixed guide lug 43 that is screwed into each end plate in proper position. Stop pins 36' are fixed to the plates in the path of movement of the levers to limit excessive movement thereof.

10 In some instances I may use end plates having gear teeth on their peripheries in lieu of the smooth edges of the plates 13 and 14. In the modification indicated in Figure 7 a portion of such a plate is indicated at 44 having teeth 45 on its periphery for co-action with the jaw cylinder 46 which is fashioned with peripheral gear teeth 47. The tucking blade 48 and the jaws 49 of the jaw cylinder are indicated in dotted lines for 15 co-acting in folding the sheet or web of paper.

It will be understood that the grippers are released at a predetermined point according to the size of the sheets of paper being collected and control of the release is under the 20 action of the cams which co-operate with the rollers 31 on the two levers. The release

usually takes place when the transverse center line of the sheet is alinement with the tucking blade and jaws of the jaw cylinder 30 as in Figure 7. At this time the sheet is given what may be its first fold.

Having thus fully described my invention what I claim as new and desire to secure by Letters Patent is:—

1. The combination with a hollow cylindrical body having a cut-out portion and its rotatable shaft, of an adjustable end plate and means for clamping it to said body, co-acting means carried by said body and plate for 40 relatively adjusting the latter, gripper mechanism located in said cut out portion and a tucking blade carried by said body.

2. A collecting cylinder having a tucking blade and a gripper mechanism and means 45 for relatively adjusting these members, said collecting cylinder including a body and adjustable end plates, clamping bolts for binding said plates to said body, and brace bars extending longitudinally through said cylinder and affixed to said plates.

In testimony whereof I have affixed my signature.

ANTHONY ZIMNIEWICZ.
